UNITED STATES PATENT OFFICE

115,193

DESIGN FOR A MACHINE TOOL UNIT

Louis H. Blood, Covington, Ky., and Lester F. Nenninger, Cincinnati, Ohio, assignors to The Cincinnati Milling Machine Co., Cincinnati, Ohio, a corporation of Ohio

Application October 22, 1938, Serial No. 80,627

Term of patent 14 years

To all whom it may concern:

Be it known, that we, Louis H. Blood and Lester F. Nenninger, both citizens of the United States, residing at Covington, in the county of Kenton, State of Kentucky, and residing at Cincinnati, in the county of Hamilton, State of Ohio, respectively, have invented a new, original, and ornamental Design for a Machine Tool Unit, of which the following is a specification, reference being had to the accompanying drawing, forming part thereof.

Figure 1 is a perspective view showing two sides of a machine tool unit, and showing our new design.

Figure 2 is a perspective view showing a third side of a machine tool unit.

We claim:

The ornamental design for a machine tool unit as shown.

LESTER F. NENNINGER.
LOUIS H. BLOOD.
